AUTOMOTIVE HEADLIGHT RETAINER

Frank Y. Soliman, Morristown, Albert H. Steinberg,
Morris Plains, and Robert E. Phillips, Plainfield, N.J.,
assignors to Allied Chemical Corporation, New York,
N.Y.

Filed Oct. 31, 1974, Ser. No. 519,882

Term of patent 14 years

Int. Cl. D26—06

U.S. Cl. D48—32 B

FIG. 1

FIG. 2

FIG. 3

FIG. 4

FIG. 1 is a perspective view of the front of an automotive headlight retainer showing our new design.

FIG. 2 is a side elevation view of the retainer shown in FIG. 1 as seen from the bottom of FIG. 1.

FIG. 3 is a side elevation view of the retainer shown in FIG. 1 seen from the left side of FIG. 1.

FIG. 4 is a plan view of the rear of the retainer shown in FIG. 1.

We claim:

The ornamental design for an automotive headlight retainer, as shown and described.
